UNITED STATES PATENT OFFICE.

EMIL G. SAUER, OF NEW YORK, N. Y., ASSIGNOR TO THE LOWELL
MANUFACTURING COMPANY, OF MASSACHUSETTS.

DESIGN FOR CARPET.

SPECIFICATION forming part of Design No. 29,401, dated September 20, 1898.

Application filed July 27, 1898. Serial No. 687,040. Term of patent 3½ years.

To all whom it may concern:

Be it known that I, EMIL G. SAUER, of New York, (Brooklyn,) in the county of Kings and State of New York, have invented and produced a new and original Design for the Body and Border of a Carpet, of which the following is a specification.

This invention comprises two parts—the design for a body A and the design for a border B; and I hereby declare that this specification and the drawings that accompany it do convey a clear understanding of my invention and are sufficient to enable it to be used.

In the drawings just referred to, Figure 1 shows my design for the body and the border. Fig. 2 shows an enlarged detail of certain figures that appear in both the body and the border.

The body A is characterized by small figures each somewhat resembling two conventional fleurs-de-lis laid in opposite directions, the figures being regularly distributed in alternating positions over the face of the carpet. The general arrangement of these fig-

ures is shown in Fig. 1, while the increased size of the small figures in Fig. 2 enables the form of these figures to be there more clearly represented.

The border B is characterized by a band of small figures similar to those in the body A and along its outer margin by leaf forms and branching scrolls, as shown.

What I claim as new, and desire to secure by Design Letters Patent, is—

1. In a design for a carpet, the body A, substantially as herein described and shown.
2. In a design for a carpet, the border B, substantially as herein described and shown.
3. The design for a carpet consisting of the body A and the border B, substantially as herein described and shown.

In testimony whereof I have signed my name to this specification in the presence of two subscribing witnesses.

EMIL G. SAUER.
